W. C. CARTER

DIAPHRAGM PUMPING DEVICE

Filed Dec. 27, 1920

Inventor:
W. C. CARTER,
By Gaskell Rhue,
Attorneys.

UNITED STATES PATENT OFFICE.

WILLIAM C. CARTER, OF ST. LOUIS, MISSOURI.

DIAPHRAGM PUMPING DEVICE.

Application filed December 27, 1920. Serial No. 433,399.

To all whom it may concern:

Be it known that I, WILLIAM C. CARTER, a citizen of the United States, residing at St. Louis, Missouri, have invented a certain 5 new and useful Improvement in Diaphragm Pumping Devices, of which the following is a full, clear, and exact description, such as will enable others skilled in the art to which it appertains to make and use the 10 same.

This invention relates primarily to pumping devices of the kind that comprise a pulsating diaphragm operated by intermittent pressure produced in a cylinder, 15 although one feature of my present invention consists of an apparatus of novel construction for supplying liquid fuel to an internal combustion engine.

The main object of my present invention is 20 to provide a diaphragm pumping device of the general type above referred to which is so constructed that the intermittent pressure in the cylinder with which the device is connected is not exerted directly on the diaphragm.

Another object is to provide a novel liquid fuel supply apparatus for internal combustion engines that is efficient, inexpensive to manufacture and of such design that there 30 is little liability of its getting out of order when in use.

And still another object is to provide a novel form of valve mechanism for a liquid fuel feed tank of the general type disclosed 35 in my prior Patent No. 1,146,133, dated July 13, 1915. Other objects and desirable features of my invention will be herein-after pointed out.

The figure of the drawings is a vertical 40 sectional view, illustrating a diaphragm pumping device constructed in accordance with my invention used in connection with an internal combustion engine for drawing liquid fuel from a source of supply into a fuel feed tank of novel design.

Referring to the drawing which illustrates the preferred form of my invention, A designates as an entirety my improved diaphragm pumping device. Said device 50 consists of a flexible diaphragm 1, an immovable wall 2 that co-operates with said

diaphragm to form a chamber α in which pressure and suction are created intermittently by the movement of the diaphragm, and an actuating means for said diaphragm comprising a spring 3 that moves the diaphragm in one direction and a piston 4 that moves said diaphragm in the opposite direction, said piston being reciprocatingly mounted in a cylinder 5 that is directly connected by means of a passageway 6 with the cylinder 7 of an internal combustion or other machine in which pressure is created intermittently. The pressure that is produced in the cylinder 7 of the engine or machine with which the pumping device A is used is exerted on the piston 4 of the pumping device, thereby causing the diaphragm 1 to flex in one direction, and compress the spring, and when the pressure in said cylinder 7 ceases, the spring 3 expands and flexes the diaphragm 1 in the opposite direction. Accordingly, when the engine or machine with which the device A is used is in operation, the pulsations or vibrations of the diaphragm 1 will create suction and pressure intermittently in a pipe 8 that communicates with the chamber α of the device A and which leads to an apparatus that is operated by the pumping device A.

The piston 4 of the pumping device A is preferably directly connected with the diaphragm 1 by a rivet or other suitable means 9, but it is not necessary that the spring 3 be attached to the diaphragm. 85 In fact, when the pumping device A is used in connection with an internal combustion engine, as herein illustrated for drawing liquid fuel from a source of supply up to a feed tank or fuel reservoir which supplies 90 fuel to the engine, I prefer to arrange the spring 3 so that it simply bears loosely against one side of the diaphragm 1, said spring being arranged in a tubular member 10 on the immovable wall 2 of the pump 95 chamber α to which the pipe 8 is connected in any preferred manner. A buffer 11 of felt, cork or other suitable material, is preferably arranged on the underside of the wall 2 so as to form a cushion against which 100 the diaphragm 1 bears, when said diaphragm is flexed by the movement of the piston 4.

The diaphragm 1 can be constructed in various ways, but I prefer to form it from a plurality of layers of fabric arranged between two metal members 1^a that are clamped together and secured to the piston 4 by the rivet 9. The peripheral edge portion of the diaphragm 1 is clamped to the peripheral edge portion of the immovable wall 2 of the pumping chamber by a clamping ring 12 which is preferably integrally connected with the cylinder 5 of the pumping device by a spider 12^a composed of arms that project radially from the upper end of the cylinder 5, thereby producing a compact pumping device that can be easily connected to the cylinder of an engine or machine by means of a nipple or pipe screwed into the lower end of the cylinder 5 of the pumping device.

I have herein illustrated the pumping device A as forming part of an apparatus for supplying liquid fuel to an internal combustion engine, said device A being used to draw fuel from a source of supply up into a feed tank or fuel reservoir B from which the fuel is supplied to the engine. I wish it to be understood, however, that the pumping device A is not limited to the particular use mentioned. The feed tank B of the apparatus herein illustrated operates on the same general principle as the feed tank described in my prior patent previously referred to, but it is equipped with a valve mechanism of novel construction. Said feed tank consists of a fuel receptacle or reservoir B, a passageway C arranged between said reservoir and a supply of liquid fuel and connected at one end with the pipe 8 leading from the chamber a of the pumping device A, and means governed by the fuel in the reservoir B for automatically cutting off the supply of fuel to said reservoir when the fuel therein rises above a certain level. The tank or reservoir B is provided at its lower end with an inlet 13 through which liquid fuel is admitted to the passageway C through a pipe (not shown) which leads to a source of supply of liquid fuel, and said tank is also provided at its lower end with an outlet 13^a through which the fuel escapes from the tank B to the engine, it being immaterial, however, at what point the fuel escapes from the tank B. The reference character 14 designates a strainer that is arranged over the fuel inlet 13 of the tank.

The passageway C of the tank is provided with an inlet valve 15 and a discharge valve 16 arranged in such a manner that the suction which is created in the passageway C by the movement of the diaphragm 1 in one direction will cause the inlet valve 15 to open, and thus admit fuel to the passageway C, and the movement of said diaphragm 65 in the opposite direction will create suffi-

cient pressure in the passageway C to open the discharge valve 16, and thus permit the fuel in said passageway to escape into the tank B through the port controlled by said discharge valve. Accordingly, when the engine or machine with which the pumping device A is connected is in operation charges of fuel will be drawn into the passageway C and discharged from same intermittently in the manner described in my prior patent previously referred to, so long as the fuel in the tank B is below a certain level. When the fuel in the tank B rises above a certain level, however, a means becomes operative to automatically cut off the supply of fuel to the passageway C. In the form of my invention herein illustrated the means just referred to embodies the same basic principle as the corresponding means of the apparatus described in my pending application for patent, Serial No. 266,908, filed December 16, 1918, namely, it is constructed in such a manner that the diaphragm of the pumping device will remain at rest or practically at rest during the time the supply of fuel to the passageway C of the tank B is interrupted. It is of slightly different construction, however, from the corresponding means of the apparatus described in my said pending application, in that it comprises a third valve 17 separate and distinct from the discharge valve 16 and arranged so that it will remain open or in an inoperative condition when the fuel in the tank B is below a certain level, and will close automatically or become operative when the fuel in said tank rises above said level. The valve 17 is arranged in the lower portion of the passageway C above the inlet valve 15 of said passageway and is combined with a spring 18 that exerts pressure on the valve 17 in a direction to tend to hold it seated over a port 19 in the passageway C. The valve 17 is prevented from seating when the fuel in the tank B is below a certain level by means of a rod or tripping device 20 arranged above said valve in longitudinal alignment with same and operatively connected with a float 21 in the tank B.

When the fuel in the tank is below a certain level, the weight of the float 21 is exerted on the valve 17 through the tripping device 20, thereby holding the valve 17 open or in an inoperative condition. At such times the valve 17 has no effect on the admission and discharge of the fuel into and out of the passageway C. When the fuel in the tank B rises above a certain level, however, the float 21 moves upwardly, and thus lifts the tripping device 20 out of engagement with the valve 17, thereby permitting said valve to move upwardly under the influence of the spring 18 and close the port 19. This causes the inlet valve 15 to be

cut off from the upper portion of the passageway C, and consequently, any suction which is thereafter created in the passageway C above the port 19 will have no influence on the inlet valve. In other words, the upward movement of the valve 17, due to a rise in the level of the fuel in the tank B, causes the supply of fuel to the passageway C to be interrupted or cut off 5 automatically, because it is impossible for the inlet valve 15 to be actuated by the suction in the upper portion of the passageway C when the valve 17 is closed or in such a position that it traps off the lower 10 portion of the passageway C in which the inlet valve 15 is arranged. Moreover, the closing or seating of the valve 17 causes the diaphragm 1 of the pumping device A to cease its normal operations and to remain 15 at rest or practically at rest until the valve 17 is unseated or opened by a drop in the level of the fuel in the tank B. This action results from cutting off communication between the supply of fuel and the upper 20 portion of the passageway C in which a partial vacuum is created each time the diaphragm 1 of the pumping device flexes downwardly, it being impossible for either fuel or air to enter the upper portion of 25 the passageway C when the valve 17 is closed, as shown in the drawing. Consequently, when the diaphragm 1 of the pumping device starts to move downwardly on what might be termed its suction stroke, 30 a vacuum will be created in the upper portion of the passageway C of sufficient intensity to overcome the force of the spring 3 and prevent the diaphragm from flexing or moving downwardly any farther. It 35 will, of course, be understood that the diaphragm of the pumping device has a slight movement, both upwardly and downwardly, when the valve 17 is closed, but this movement is so slight that it has no fatiguing 40 action on the diaphragm.

The particular details of construction of the tank B and the particular type of valves that are used for governing the admission and discharge of the fuel into and out of 45 the passageway C and for trapping off a portion of said passageway are immaterial, but I prefer to use ball check valves for the valves 15 and 16 and arrange the valve 17 in the lower portion of the passageway C directly above the inlet valve 15. The 50 passageway C is preferably formed in a member 22 that projects downwardly from the underside of the removable top 23 of the tank B, and the seats for the valves 15 and 16 are preferably formed in separate 55 parts 15^a and 16^a, respectively, that are detachably connected to the member 22, the part 16^a being arranged horizontally on the member 22 at a point below an integral lug 16^b on said member that serves as a

stop for the discharge valve 16, and the part 15^a being mounted in the lower end of the member 22 and projecting downwardly through the bottom of the tank B, so that it will serve as a support for the fitting or 70 pipe connection 24 in which the inlet opening 13 and the discharge opening 13^a are formed. The tank B is provided with an air vent 25 formed preferably by a perforated member that is mounted in the removable top or cover 23 of said tank. 75

A pumping device A of the construction previously described is capable of use for various purposes, but it is particularly adapted for use with an internal combustion 80 engine, owing to the fact that the hot gases in the cylinder of the engine with which the device is connected never come in contact with the diaphragm of the device, and moreover, the high pressure that exists in the cylinder of the engine is never exerted directly on the diaphragm. The fuel feed tank or reservoir B is of such simple construction that it can be manufactured at a low cost, and as it is composed of only a few rugged 85 parts of simple design, there is little liability of its getting out of order when in use. 90

Having thus described my invention, what I claim as new and desire to secure by Letters Patent, is: 95

1. A pumping device, comprising a diaphragm, an actuating means for said diaphragm comprising a piston mechanically connected to the diaphragm, a cylinder in which said piston is reciprocatingly mounted, a second cylinder wherein pressure is created intermittently, and a connection between said cylinders. 100

2. A pumping device, comprising a diaphragm, a spring arranged on one side of said diaphragm for moving it in one direction, a piston arranged on the other side of said diaphragm for moving it in the opposite direction, a cylinder for said piston, a second cylinder wherein pressure is created 105 intermittently, and means for establishing direct communication at all times between said cylinders. 110

3. A pumping device consisting of a cylinder, a member combined with said cylinder so as to form one wall of a pumping chamber, a flexible diaphragm connected to said member so as to form the other wall of said chamber, a piston in said cylinder mechanically connected to said diaphragm and adapted to move the diaphragm in one direction, and a spring on the other side of said diaphragm for moving it in the opposite direction. 115

4. A fuel supply apparatus for internal combustion engines, comprising a fuel reservoir, a passageway arranged intermediate said reservoir and a supply of liquid fuel and provided with an inlet valve and a discharge valve, a pumping device comprising 120 125

a chamber, a connection between said chamber and passageway, a diaphragm in said chamber for creating suction and pressure intermittently in said passageway, an operating piston for said diaphragm connected to same, a cylinder for said piston, and means for establishing communication be-

tween said cylinder and the cylinder of an internal combustion engine so as to cause said piston to be actuated by the intermittent pressure produced in the cylinder of the engine. 10

WILLIAM C. CARTER.
